UNITED STATES PATENT OFFICE.

WILLIAM D. MCCLAIN, OF CHICAGO, ILLINOIS, ASSIGNOR TO WILLIAM MCCLAIN MANUFACTURING COMPANY, OF CHICAGO, ILLINOIS, A CORPORATION OF ILLINOIS.

LIQUID-DISPENSER.

1,334,769.

Specification of Letters Patent. Patented Mar. 23, 1920.

Application filed March 18, 1916. Serial No. 85,010.

To all whom it may concern:

Be it known that I, WILLIAM D. MCCLAIN, a citizen of the United States, and resident of Chicago, in the county of Cook and State 5 of Illinois, have invented certain new and useful Improvements in Liquid-Dispensers, of which the following is a full, clear, and exact specification.

This invention relates to improvements in 10 liquid dispensers, and particularly those types in which the liquid container or reservoir is maintained in a fixed position and the contents thereof discharged either by gravity or by mechanical pressure, the one 15 to the exclusion of the other.

The prime object of my invention broadly 20 stated is to utilize the combined operation of both gravity and pressure for discharging the contents of the container or reservoir, whereby the dispenser is adapted for materials ranging in viscosity from the 25 thinnest liquid to as low as salves.

More specifically stated the object of my 25 invention is to provide a means for discharging the liquid from the container or reservoir of a dispenser by gravity accelerated by the force imparted by the plunger, and by which air at atmospheric pressure assisted by capillary attraction, is utilized 30 to prevent accidental leakage.

A further object of my invention is to 35 provide a liquid dispenser with means for introducing into the container or reservoir of a dispenser above the level of the liquid therein following every discharge of liquid therefrom, air at atmospheric pressure of a volume sufficient to produce and insure the 40 discharge of a predetermined quantity of the liquid at each stroke of the piston, however frequently repeated.

Another object of my invention is to provide a means by which the air supply passage to and the discharge passage from the container or reservoir are automatically 45 hermetically sealed, when the plunger is at rest at the limit of its outward, that is to say its downward stroke.

A further object of my invention is to 50 have the discharging devices for a liquid dispenser of a form of construction so simple and cheap that antiseptic materials may be used for their construction with commercial

success, and the several parts thereof may be conveniently and quickly assembled and be secured against removal from the container.

With these ends in view, my invention finds embodiment in certain features of novelty in the construction, combination and arrangement of parts by which the said 60 objects and certain other objects are attained, all as hereinafter fully described with reference to the accompanying drawing, and more particularly pointed out in the claims.

In said drawing:

Figure 1 illustrates in side elevation, partly in vertical section, a liquid dispenser in which my invention finds embodiment.

Fig. 2 is a bottom plan view thereof with a portion of the container and supporting bracket arm therefor broken away.

Fig. 3 is a bottom plan view of the end of the neck of the container for the dispenser 75 with the plunger and cap removed therefrom.

Fig. 4 is a vertical section of the plunger, and—

Fig. 5 is a transverse section thereof on 80 the line 5—5 of Fig. 4.

Similar characters of reference indicate the same parts in the several figures of the drawing.

6 indicates a suitable container or reservoir for the liquid to be dispensed, preferably constructed of suitable material, but preferably of glass, provided top and bottom with necks 7 and 8, externally having screw-threads as indicated at 9 and 10, preferably formed integrally therewith, but may be separately therefrom, and secured thereto.

The filling neck 7 is closed by a removable screw-threaded cap 11 against a gasket 95 12 seated at the base of the neck for hermetically sealing the filling opening of the container.

Screw-threaded upon the neck 8 is a cap 13, provided with an inwardly projecting 100 tubular sleeve 14 open at both ends, the cap being hermetically sealed against the end of the neck by means of a gasket or other suitable annular packing 15.

Projecting through the neck into the body of the container is a U-shaped open bracket 16, the free ends of which are bent outwardly as indicated at 17, across the end 5 of the neck 8, and against which they are clamped by the operation of the nut tightening the packing to form a hermetically sealed joint between the cap and the neck, the U-shaped bracket being provided at the 10 upper end with a perforation 18, furnishing a bearing for a stem 19.

Removably seated against the upper end of the plunger 20 by means of a pin 21 passing through a perforation 22, in the 15 stem 19 is a washer 23 provided upon its underside with a downwardly projecting flange 24 adapted to surround the outer surface of the upper end of the sleeve 14, and for containing a packing 25, for hermetically sealing the joint between the washer 20 and the sleeve, when the plunger is at the limit of its outward, that is to say in this instance, its downward stroke.

Surrounding the stem 19 and abutting 25 against the washer and the upper end of the bracket 16 is a coiled spring 26, for normally maintaining the packing 25 seated against the end of the sleeve 14, and the flange 24 encircling said end.

30 The flange 24 serves both as a means for confining and centering the packing against the end of the sleeve, but the omission of the flange would be no substantial departure from my invention.

35 Plunger 20 is provided with a liquid discharge passage 27, which extends at an oblique angle to the axis of the plunger with its discharging end 28 at the axis of the plunger, and its inlet or receiving end 40 29 opening at the side of the plunger a short distance below the upper end of the plunger, with the result that the plunger must be moved upwardly above its seated position before the passage 27 is exposed 45 to, or can receive any part of the liquid contents of the container.

The plunger is also provided with an elongated groove forming a chamber 30, which as shown in the drawings terminates 50 a short distance below the top of the plunger, the lower end of which chamber is open for the admission of air at atmospheric pressure when the plunger is seated, but is closed before the discharge passage 55 27 is exposed to the liquid contents of the container.

In practice the cubic contents of the air chamber 30, and that of the inlet to the discharge passage 27, is equal or substantially so, and for reasons which will be made apparent later on.

The plunger is provided at its outer end with knobs 31—31 respectively joined by stems 32—32 to the adjacent end of the 60 plunger to provide convenient surfaces for

pressing the plunger upwardly into the container with the fingers or by the palm of the hand as may be, and that there may be no obstruction to the discharge of the liquid from the passage 27.

70 As shown in the drawings the dispenser is supported from the arm 33 projecting from a bracket 34 secured to any suitable fixed support by set-screws 35, which support may be the side wall of, or a post in a room wherein the dispenser is located.

For convenience and cheapness of construction the collar 13 may be cast or otherwise secured to the supporting arm, as shown in Fig. 1.

80 It is now observed that the dispensing devices are of the fewest possible number of parts, very cheap of construction, quickly and easily assembled, and may be permanently secured, and as should be to 85 the container whether of glass or metal, by introducing between the screw-threads of the collar 13 and the neck of the container, cement before finally screwing the collar to its seated position.

90 With the container filled with any liquid or partly filled, as indicated in Fig. 1, or as for example, with liquid soap and hermetically sealed by the cap 11, and the plunger in its seated position as shown 95 therein, a discharge of the liquid contents of the container may be had by pushing upwardly against the knobs 31 until the plunger is moved above its seat sufficiently to expose the inlet of the discharge passage 100 27 to the liquid contents of the container, before which however, the lower end of the air chamber 30 passes within and is closed by the sleeve 14.

105 With the continuous upward movement of the plunger from its seat the liquid likewise discharges from the container through the passage 27, the upward stroke of the plunger being preferably limited by the contact of the arms 32 with the opposing 110 surface of the cap, but may be by the spring 26 when fully compressed.

The discharge of the liquid from the passage 27 will cease whenever for any reason the plunger is brought to a standstill before reaching the limit of its upward movement, but will commence again as soon as that upward movement of the plunger is resumed.

115 The amount of liquid discharged from the passage 27 depends upon the degree of pressure exerted by the plunger against the contents of the container, which amount may be and is determined by the cubical contents of so much of the plunger and 120 the length of its compressive stroke.

125 For discharging the same quantity of liquid from the passage 27 for every successive stroke of the plunger, the cubic contents of the air chamber, and that of the 130

plunger above the inlet to the discharge passage must be equal, plus possible leakage of air around the plunger during its upward stroke, it being found in practice, 5 for example, that when the cubic contents of the air chamber is substantially less, a vacuum is produced in the container increasing with every successive stroke of the plunger, with the result that the amount of 10 liquid discharged from the passage 27 is correspondingly decreased with every successive stroke of the plunger.

Now, although the air passage is in open 15 communication with the contents of the container during and throughout the discharge of liquid from the passage 27, and which reduces the pressure in the cylinder to substantially atmospheric pressure, the air does not discharge from the air passage before 20 the plunger begins its downward movement.

The reason for this seemingly appears to be that when, capillary attraction in the discharge passage operates to prevent a gravity 25 discharge of the liquid from the passage 27, there remains in the container a very slight degree of pressure, but sufficient to resist the natural tendency of the air to ascend through the heavier liquid until a vacuum is produced by the withdrawal of the plunger 30 therefrom, which vacuum is thereafter filled by the air discharged from the air chamber, and whereby the contents of the container is then normally exposed to atmospheric pressure.

35 It is also possible that the deflection of the passage 27 at an oblique angle to a line through the center of gravity of the liquid, reduces the gravity of the liquid and coöperates with capillary attraction in the passage to prevent the discharge of liquid therefrom by gravity, when and for whatever length of time that passage may be exposed to the liquid contents of the container.

That by deflecting the passage 27 from 45 the center of gravity of the liquid, a force is produced coöperating with capillary attraction to prevent the discharge of liquid from that passage during the time the plunger is off its seat, and throughout its movement until the passage is closed by the sleeve 50 29, is seemingly apparent from the fact that repeated experiments have demonstrated that when the diameter of the passage is an eighth of an inch instead of three-thirty- 55 seconds of an inch, as indicated in the drawing, there is following a discharge, no leakage through the passage when the plunger is at a standstill in any position it may have throughout the exposure of that passage to 60 the liquid contents of the container.

With the plunger provided with a packing, and in its seated position shown in Fig. 1, and the discharge end of the air passage sealed by the sleeve, as therein shown, the 65 liquid contents of the container will to all

intents and purposes be sealed therein until the plunger is moved upwardly off its seat.

In conclusion it is to be observed that my invention is not limited to the specific details of construction herein shown, and described, as containing its tangible embodiment, but extends to and includes any form and arrangement of devices coöperating with the liquid contents of a container or other reservoir directly or indirectly connected therewith, wherein the discharge of liquid therefrom is effected by the simultaneous coöperating of mechanical pressure with the gravity of the liquid and capillary attraction is utilized for preventing leakage through a discharge passage exposed thereto.

Having described my invention, what I claim and desire to secure by Letters Patent is:

1. A liquid dispenser comprising in combination a container, a discharge passage therefor, means for simultaneously compressing the contents of said container, exposing said passage to the liquid therein, and forcibly discharging the liquid from said passage.

2. A liquid dispenser comprising in combination a container, a discharge passage therefor, mechanical means for simultaneously compressing the contents of said container, exposing said passage to the liquid therein, and forcibly discharging the liquid from said passage.

3. A liquid dispenser comprising in combination a container, a liquid discharge passage and an air supply chamber therefor, a plunger adapted for simultaneously closing the inner ends of said passage and chamber, and concurrently therewith openly exposing the outer ends of said chamber and said passage to air external thereto.

4. A liquid dispenser comprising in combination a container, a plunger, a sleeve for said plunger projecting into the container, said plunger being provided with a longitudinal liquid discharge passage, and an air chamber separated therefrom, said chamber and passage being so arranged that when the plunger is seated, the upper ends 110 of said chamber and passage are closed and the lower ends open, and that following the lifting of the plunger from its closing position the air chamber is closed at its outer end, and open at its inner end in advance of 115 the opening of the inner end of the discharge passage.

In witness whereof I have hereunto set my hand and affixed my seal, this 16th day of March, A. D. 1916.

WILLIAM D. McCALAIN. [L. S.]
